CLAIM

The ornamental design for a tablet case, as shown and described.

DESCRIPTION

FIG. 1 is a perspective view of a tablet case, showing my new design;

FIG. 2 is another perspective view thereof;

FIG. 3 is a perspective view of the design in use status;

FIG. 4 is a front view thereof;

FIG. 5 is a rear view thereof;

FIG. 6 is a left side view thereof;

FIG. 7 is a right side view thereof;

FIG. 8 is a top plan view thereof;

FIG. 9 is a bottom plan view thereof; and,

FIG. 10 is an enlarged view of portion 10 shown in FIG. 3.

The broken lines depict portions of the tablet case and form no part of the claim. The dot-sash-dot lines in FIG. 3 represent the boundary of the enlarged FIG. 10 detail.
